SWITCH

William Correll Edwards, Anderson, Ind., assignor to General Motors Corporation, Detroit, Mich., a corporation of Delaware

Application March 17, 1934, Serial No. 716,074

7 Claims. (Cl. 200—11)

This invention relates to electric switches particularly for controlling vehicle lamp circuits including head lamp having main and auxiliary filaments.

5 An object of the invention is to provide a switch which, in one position turns on the parking lights, in another position turns on the main filaments, in another position turns on the auxiliary filaments, and in still another position 10 turns on the main filament of one head lamp and the auxiliary filament of another head lamp.

A further object is to provide a lighting circuit switch of compact construction adapted to be mounted upon the lower end of a steering column 15 and to be operated by a shaft passing through the column.

A further object is to house the terminals of the switch by means which will provide ready access to the wire attaching screws of the terminals.

20 Further objects and advantages of the present invention will be apparent from the following description, reference being had to the accompanying drawings wherein a preferred embodiment of 25 the present invention is clearly shown.

In the drawings:

Fig. 1 is a side view of the switch embodying the present invention.

Fig. 2 is a view looking in the direction of arrow 2 row 2 of Fig. 1.

Fig. 3 is a perspective view showing the parts of the switch in disassembled relation.

Fig. 4 is a view looking in the direction of arrow 4 of Fig. 5 and showing only the switch back 35 and terminal block.

Fig. 5 is a longitudinal sectional view of the switch the section being taken approximately on the line 5—5 of Fig. 4.

Fig. 6 is a view of the switch showing the inside face of the switch back, this view being 40 taken in the direction of the arrow 6 of Fig. 5.

Fig. 7 is a view of the movable switch contact taken in the direction of the arrow 7 of Fig. 5.

Figs. 8 and 9 are sectional views taken respectively on the line 8—8 and 9—9 of Fig. 7.

Figs. 10 to 14 inclusive are wiring diagrams illustrating the use of the present invention.

Figs. 10a to 14a respectively are diagrammatic views showing the switch contact carrier and 50 are drawn in various positions conforming respectively to the diagrams of Figs. 10 to 14 inclusive.

Referring particularly to Fig. 3, 20 designates 55 a cup-shaped switch housing having a flat end wall 21 attached in any suitable manner to a

bracket 22 which preferably attaches the housing 20 to the lower end of a steering column of an automobile. The wall 20 is provided with a central hole 23 through which extends a drive shaft 24 having a key slot 25. The shaft 24 extends 5 into the steering column and is operated by a lever located within the space within the rim of the steering wheel. The wall 21 is also provided with integral lugs 26 and 27 which serve as stops to limit rotation of the movable contact of the 10 switch in a manner to be described later. The wall 21 is provided also with an annular row of holes 28 which cooperate with projections or axially movable parts in order to yieldingly maintain the switch in its various positions as will be 15 described later.

The shaft 24 cooperates with the shaft connector or switch driving member 30 having a central bore 31 into which the shaft 24 extends. 20 Protruding into this bore is a key formed integrally with the shaft connector 30 by forcing some of the metal of the side wall of the connector 30 inwardly thereby leaving a depression 32 on the exterior thereof. The connector 30 is provided adjacent its right hand end with flats 33 and 34 and by adapting said right hand end of the connector 30 to be pushed into the central opening 35 formed in a drive plate 36, said central opening having flats 33a and 34a which are engageable by the flats 33 and 34 of the connector or driving member 30. The driving plate 36 is provided with lugs 37 and 38 adapted to engage the lugs 27 and 26 respectively, of the end wall 21 of the housing 20 thereby limiting rotation of the plate 36 by the shaft 24. Plate 36 is 35 provided with integral lugs 39, each of which is reduced in width near its free end so as to provide shoulders 40 and a portion 41 in less width than other portions of the lug. The lugs 39 are received by notches 42 in a detent plate 43 having a central opening 44 adapted to receive the shaft connector 30. The detent plate 43 is provided with depressions 45 which extend toward the right of the drawings thereby providing spherical bosses extending from the face of the plate 45 which is adjacent the end wall 21 of the switch housing 20. The bosses formed by the depressions 45 extend through holes 46 in the driving plate 36 and are received by certain ones of the annular row of holes 28. The drive plate 36 is 50 spaced from the wall 21 by a washer 47 adapted to embrace the shaft connector 30. The detent plate 43 is yieldingly urged toward the end wall 21 by a spring 48 the right hand end of which bears against detent plate 36 and the left hand 55

end is engaged by a spring retainer cup 49 the central opening 50 of which embraces the reduced end portion 51 of the shaft connector 30 and is held in this position due to engagement with the back of the switch when the parts are assembled as will be described later. The right hand end of the spring 48 is retained in the somewhat concentric relation with respect to the shaft connector 30 by providing the detent plate with an annular flange 52 as shown in Fig. 8, said flange being adapted to extend slightly within the first convolution of the spring.

Referring to Fig. 5, it will be seen that the washer 47 separates the drive plate slightly from the switch case wall 21 so as to reduce the friction while at the same time permitting the boss 45a formed by the depression 45 in the detent plate 43 to extend into the holes 28. Part of the bracket 22 through which the shaft 24 extends is provided with an annular pocket 53 which receives a felt washer 54 adapted to fit snugly around a shaft connector 30 in order to keep out dirt and other foreign matter.

Referring to Figs. 7, 8 and 9 there is shown a contact carrier disc 60 of insulating material. The disc 60 is provided with an annular row of oblong holes 61 and two directly opposite oblong holes 62. The holes 61 are adapted to receive the end portions 41 of the lugs or tangs 39 of the driving plate 36. The shoulders 40 of the tangs 39 engage the contact carrier 60 and properly space the carrier 60 from the plate 36. The carrier 60 drives a contact ring 63 through its tangs 64 which extend through the oblong holes 62 and are bent at 65 against the opposite face of the carrier 60. The ring 63 is urged away from the carrier 60 by a spring 66, which is located between the parts 63 and 60 and bears against the adjacent face thereof. The spring 66 is retained substantially concentrically with the ring 63 by providing the ring 63 with integrally extending lugs 67 which extend within the end convolutions of the spring 66. The ring 63 is provided with spherical bosses which provide switch contacts 200, 201 and 202.

The carrier 60 drives a second movable contact member 70 which is arcuate in shape and is supported by three headed studs 71 along which the member 70 may slide longitudinally, said member being urged toward the heads of the studs 71 by springs 72 surrounding said studs and located between the members 70 and 60. The end portions 73 of the member 70 extend beyond the plane of the main portion 70 and are each provided with spherical bosses providing contacts 203 and 204. For a purpose to be described the ring contact member 63 and the arcuate contact member 70 are connected by a flexible conductor 75.

The switch case 20 is provided with an outwardly flared concentric wall 80 adapted to receive a switch back or contact block 81 which is retained in position by a wire ring 82 received by a groove 83 provided in the annular portion 84 of the switch case 20. Block 81 provides a central bearing for the portion 51 of the driving member 30. The contact block 81 which is of non-conducting material carries stationary contacts 101 to 107 respectively as shown in Fig. 6. These contacts are in with the inner wall of the switch piece. Some of these contacts are provided by the heads of rivets which are used to secure to the outer face of the switch piece a number of connecting straps leading to the switch terminals to be described. In Fig. 4 these rivets are numbered 101a to 107a respectively their numbering

indicating their connection with contacts 101 to 107, respectively. Contacts 102, 104, 106 and 107 are elongated, and rivets 102a, 104a, 106a and 107a pass respectively through these contacts, as shown in Fig. 5. The straps which are connected with the rivets 101a to 107a are numbered 101b to 107b, respectively. These straps connect their respective rivets with eyelets of the tubular rivets 101c to 107c, respectively. These tubular rivets are molded in the non-conducting terminal block 110. Each rivet is threaded and receives a terminal screw. The screws corresponding with the contact rivets 101a to 107a are numbered 101d to 107d. Each terminal screw is associated with a wire retainer plate 111 and the plates are separated from each other by lugs or partitions 112. Certain of these lugs bear indicia as indicated in order to identify the terminals. The terminal block 110 is provided with an outwardly extending flange 115 upon which wires such as shown in 116 in Figs. 1 and 2 are adapted to rest when the switch is mounted upon the lower end of the steering column.

The terminal block 110 and the wires connected therewith are enclosed by a housing consisting of members 120 and 121. The member 120 is somewhat in the form of a cylindrical shell having a flat end portion 122 and an inclined end portion 123. The cylindrical side wall 124 is provided with an aperture for receiving lug 125 provided by the annular portion 84 of the switch case 20. In this way the arcuate edge portion of the member 120 is retained upon the bead 83a which is formed when providing the ring groove 83. The member 120 is provided with holes 126 which serve as drain holes since, when the switch is applied to the steering column, the wall 123 will occupy the lowermost position. The screw 127 passes through a suitable hole in the member 120 and cooperates with a nut 128 carried by the terminal block 110. In this way the member 120 is fixed to the switch case. It is not necessary to remove the member 120 when tightening the connections between the wires and switch terminals. To accomplish this it is only necessary to move the housing member 121 which is hingedly attached to member 120. The cylindrical edge is provided with two lugs 130 which are adapted to be received by oblong holes 131 in the end wall 132 of the member 121. The arcuate edge portion of the member 121 is retained upon bead 83a of the switch case by a screw 133 which passes through a notch 134 of the member 121 and is received by a threaded hole provided in an ear 135 of the switch case member 120. The member 121 is provided with an outwardly extending flange 136 which is complementary to the flange 115 of the terminal block 110. Hence the two flanges 115 and 136 provide a conduit through which wires may be brought out from the terminal compartment within the members 120 and 121. The member 120 is provided with a lip 137 which is interrupted by the flange 136. This lip overlies the mating edge portion of the member 120 thereby forming a joint which tends to exclude dirt and other foreign matter.

Referring now to Figs. 10 to 14 inclusive, the operation of the switch will now be described. Referring first to Fig. 11 which shows the switch in the off position, it is noted that the movable contacts 200 to 204 inclusive are out of circuit-making position, the stationary contact 107 being engaged only by the contact 201. The connections between the battery and lamp circuits and stationary contacts of the switch are as fol-

lows: The battery 150 is grounded at 151, connected by wire 152 with contact 104 from which current is distributed by the movable contacts of the switch to the lamp circuits. These circuits include parking lamps 153 connected together by wire 154 which is connected by wire 155 with contact 105. The contact 107 is connected by wire 156 with tail lamp 157. The lamps thus far mentioned have only one grounded filament. The head lamps shown at 160 and 161 each have two filaments which are grounded. The main filaments of lamps 160 and 161 which produce beams substantially straight ahead are numbered 162 and 164, respectively. The auxiliary filaments which will direct beams downwardly upon the road within a few feet ahead of the car are indicated by numbers 163 and 165, respectively. Wires 167 and 169, respectively, connect filaments 163 and 165, respectively, with contacts 103 and 106, respectively. Wires 166 and 168, respectively, connect the filaments 162 and 164, respectively, with contacts 102 and 101, respectively. In order to turn on the parking lights, the switch handle is turned in a counter-clockwise direction as viewed in the diagram, thereby moving the movable contacts into the position shown in Figs. 10 and 10a. In this position the battery contact 104 is connected with contact 107 connected with the tail lamp 157 which burns as indicated by arrow 157a. Contact 104 is also connected with contact 105 leading to the parking or side lamps 153 which burn as indicated by arrow 153a. The head lamps are not connected with the battery.

Figs. 12 and 12a show the city driving position of the movable contacts. It is apparent that the movable contacts connect the battery with the stationary contacts of the switch which are connected, respectively, with the tail lamp and the head lamp auxiliary filaments 163 and 165 which give the depressed beams as indicated by arrows 163a and 165a. The switch is moved into city driving position by a clockwise movement of the movable contact as shown in the diagram.

Further clockwise movement of the switch contacts, as viewed in the diagram will bring them into the country passing position as shown in Figs. 13 and 13a. In this position, filament 162 of the left hand head lamp 160 and filament 165 of the right hand head lamp 161 are caused to burn as indicated by arrows 164a and 165a. This shows that the left hand lamp will throw a beam straight ahead while the right hand lamp will give illumination to the right hand margin of the road.

Further clockwise movement of the movable switch contacts, as viewed in the diagram, will bring these contacts into position for country driving as shown in Figs. 14 and 14a. Fig. 14 shows that the filaments 162 and 164 of the head lamp are connected with the battery thereby causing beams to be thrown straight ahead by both lamps as indicated by arrows 162a and 164a.

It is therefore apparent that the present switch connects the parking lamps with the battery by moving the switch handle above the steering column toward the left from the "Off" position. Movement of the switch handle from "Off" position toward the right, as viewed from the driver's seat, will cause the switch contacts to be first brought into the city driving position. The next position toward the right following the city driving position is the country passing position and the final position toward the right is the country driving position. The advantage of arranging the

circuits to be set up by these different positions of the switch handle will be apparent. It is easy to remember that the parking lights will burn when the switch handle is moved as far as possible toward the left from "Off" position; and that the country driving position of the switch is obtained by moving the switch handle as far as possible toward the right. When passing another car in driving in the country, the switch handle is moved one position toward the left while passing, and is then moved back again toward the right after the approaching car has passed. It is easy to remember that city driving position is obtained by moving the right hand switch lever into the first position toward the right toward the "Off" position.

This control of circuits is obtained by the use of one switch member.

The switch is a relatively compact structure due to the fact that the movable contacts are arranged in two concentric rows one within the other and are arranged to cooperate with stationary contacts located in the same plane. Since all five of the movable contact bosses are not mounted on the same contact member satisfactory contact pressure between all of the movable contacts and the stationary contacts can be effected. As shown, the contact ring 63 carries three of the contact bosses which engage the inner row of stationary contacts with substantially equal pressure which is exerted by a single coil spring 66. The other two contact bosses 203 and 204 are mounted upon an independent member 70 which is urged by independent springs 72 toward the outer row of stationary contacts. The members 63 and 70 are connected by a flexible wire 75 which does not interfere with action of these members in pressing their contact bosses with satisfactory pressure against the stationary contacts.

While the embodiment of the present invention as herein disclosed, constitutes a preferred form, it is to be understood that other forms might be adopted, all coming within the scope of the claims which follow.

What is claimed is as follows:

1. A switch comprising, in combination, two concentric arcuate rows of stationary contacts in the same plane, a rotatable contact carrier, a contact ring having contact bosses and supported by the carrier coaxially thereof, means provided by the ring and carrier whereby the carrier rotates the ring and separation of the ring from the carrier is limited, a helical spring located between the ring and carrier, an arcuate contact segment located outside the ring, means resiliently supporting the segment by the carrier, and a flexible wire connecting the ring and segment.

2. A switch comprising, in combination, a switch case having end walls providing aligned openings, one of which provides a bearing, a driving member journaled in said bearing, a driving plate mounted on the member and connected therewith, a detent plate movable along the driving member and having detents cooperating with openings in one end wall of the case, a helical spring urging the detent plate toward said end wall, a contact carrier, means connecting the driving plate with the detent plate and contact carrier and permitting movement of the detent plate along the driving member, movable contacts mounted upon the carrier, and stationary contacts supported by the other end wall of the case.

3. A switch comprising, in combination, a switch case having end walls providing aligned openings, one of which provides a bearing, a

driving member journaled in said bearing, a driving plate mounted on the member and connected therewith, a detent plate movable along the driving member and having detents cooperating with openings in one end wall of the case, a helical spring urging the detent plate toward said end wall and bearing against the opposite end wall, a contact carrier, means connecting the driving plate with the detent plate and contact carrier and permitting movement of the detent plate along the driving member, movable contacts mounted upon the carrier and including a contact ring surrounding said spring, a helical spring surrounding the first helical spring and urging said contact ring away from the contact carrier, and means provided by the ring and carrier whereby the carrier rotates the ring and separation of the ring from the carrier is limited.

4. In a switch, a switch case including a contact block, a terminal block supported by the contact block, and carrying terminals, a housing for the terminals including part fixed with respect to the case and a part which is movable to expose the terminals while the other part remains fixed, and cooperating extensions provided by the terminal block and movable housing part, said extensions cooperating to form a wire conduit extending exteriorly of the housing.

5. A lighting switch comprising, a housing com-

prising an open cylindrical cup, a switch back seated within the open end of the cup and providing a plurality of contact members, said housing and switch back enclosing switch structure cooperating with the contacts, a terminal block supported from the switch back and providing terminals connecting each with a contact, a split cover enclosing the terminal block and telescopically engaging the open end of the housing cup, said cover comprising a half section rigidly supported upon the terminal block, and a removable section hingedly connected to the rigid section, and means for retaining the removable section in fixed engagement with the housing cylindrical portion.

6. The combination set forth in claim 5 wherein the hinged connection of the two half sections comprise an apertured flange on the removable section and cooperating tongues for registry with the apertures on the fixed section.

7. The combination set forth in claim 5 wherein the terminal block has a lateral semicylindrical extension extending through the fixed half cover section, and the removable cover section has a semicylindrical lateral extension cooperating with the extension of the terminal block providing a tubular guideway for leads connected with the terminals.

WILLIAM CORRELL EDWARDS.
